UNITED STATES PATENT OFFICE.

MATTHEW VON PEIN, OF RICHMOND, INDIANA.

NOTCHING-MACHINE.

SPECIFICATION forming part of Letters Patent No. 766,896, dated August 9, 1904.
Application filed March 14, 1904. Serial No. 197,977. (No model.)*To all whom it may concern:*

Be it known that I, MATTHEW VON PEIN, a citizen of the United States, residing at Richmond, in the county of Wayne and State of Indiana, have invented certain new and useful Improvements in Notching-Machines, of which the following is a specification.

In the manufacture of pianos it has heretofore been customary to secure the bridge to the sounding-board and thereafter cut out by hand portions along the edges of the bridge, so as to form uniform and comparatively narrow supporting-ledges for the several sets of strings, a ledge being formed for each set of strings—that is, the strings designed to produce a single tone. Such work is exceedingly slow and tedious and requires considerable skill.

The object of my present invention is to provide a machine by means of which this work upon the bridge may be more rapidly and uniformly done.

The accompanying drawings illustrate my invention.

Figure 1 is a perspective view showing my improved tool in operation. Fig. 2 is a plan thereof with a portion of the bridge; Fig. 3, an elevation with the bridge in section; Fig. 4, a plan of the supporting-joints; Fig. 5, a section on line 5 5 of Fig. 4, and Fig. 6 a section on line 6 6 of Fig. 5.

In the drawings, 10 indicates the sounding-board of a pianoforte, and 11, the bridge secured thereto. This bridge, as heretofore stated, requires the formation in its top of a series of ledges 12, over which the strings of the pianoforte are stretched, and these ledges are formed by producing notches or depressions 13 in the upper face of the bridge, the sides of the ledges being at right angles to the strings, while the main lines of the bridge curve as desired to produce the necessary relative length of strings.

My improved tool consists of a suitable supporting-base 15, having a smooth bottom in order that it may slide easily over the sounding-board 10. Erected from base 15 are a pair of ears 16, between which is pivoted a yoke 17, said yoke being supported upon a central horizontal shaft 18, mounted in ears

16. Pivoted upon horizontal pins 19 in yoke 17 at right angles to shaft 18 is the bifurcated end 20 of a tool-carrying handle, or arm 21. Journalled in suitable bearings on handle 21 is a shaft 22, parallel with the pins 19, and this shaft carries at one end a suitable pulley 23 and at the other end a cutter 24.

Mounted upon handle 21, preferably between cutter 24 and yoke 17, is a suitable motor 25, (preferably an electric motor,) provided with a pulley 26 in line with pulley 23 and connected thereto by a suitable belt 27. The motor 25 is preferably placed upon the handle 21 in such way that it will be balanced about shaft 18, a suitable stop 25' being provided, if desired, to prevent too much swing about the shaft. The handle 21 is provided at a point convenient to the operator with a suitable adjusting-screw 28, by means of which the depth of the cut of the cutter 24 may be easily determined. For convenience of operation the cutter 24 is preferably arranged in line with shaft 18.

In operation after the bridge 11 is secured in position the tool described is run up adjacent the bridge, and the operator grasping the tool in the manner shown in Fig. 1, one hand upon a handle 21 and the other upon a support 29, brings the cutter 24 into engagement with the upper face of the bridge in such manner as to cut the desired notches therein.

It will be immediately understood from the illustration that by the means described the necessary notches may be cut in the bridge very rapidly and very uniformly, and experience has shown that an operator comparatively unskilled can produce a very much greater quantity of work and of a more uniform quality than has heretofore been possible by hand.

By reason of the universal joint between the handle 20 and the supporting-block 15 any desired angle of cut may be obtained, yet the cutter and motor are always in alinement.

I claim as my invention—

1. A tool of the class described consisting of a suitable portable horizontal supporting-plate, an arm jointed thereto by means of a joint hinged in two planes, a motor mounted

on said arm, a cutter journaled on said arm, and connections between the motor and cutter, for the purpose set forth.

2. A tool of the class described consisting of, a suitable portable horizontal supporting-plate, an arm jointed thereto by means of a joint hinged in two planes, a cutter journaled in said arm in line with one of the axes of the joint, a motor also mounted on the arm, and connections between the motor and cutter.

3. A tool of the class described consisting of, a suitable portable horizontal supporting-

plate, an arm jointed thereto by means of a joint permitting movement in two planes, a cutter journaled on said arm, and means for 15 operating the cutter.

In witness whereof I have hereunto set my hand and seal, at Richmond, Indiana, this 10th day of March, A. D. 1904.

MATTE VON PEIN. [s. s.]
